CHARGE FORMING DEVICE

Filed Oct. 20, 1928

UNITED STATES PATENT OFFICE

JEROME I. ANSON, OF DAYTON, OHIO, ASSIGNOR, BY MESNE ASSIGNMENTS, TO DELCO
PRODUCTS CORPORATION, OF DAYTON, OHIO, A CORPORATION OF DELAWARE

CHARGE FORMING DEVICE

Application filed October 20, 1928. Serial No. 313,837.

This invention relates to charge forming devices for internal combustion engines and more particularly to the type of charge forming device which comprises a plurality of 5 primary mixing chambers, each of which is adapted to deliver a primary mixture of air and fuel to one of a plurality of secondary mixing chambers, one of which is associated with each engine intake port and each of 10 which receives air, when required, through one of the branches of an air manifold having a single air inlet. A common fuel reservoir supplies liquid fuel to all of said primary carburetors.

15 Examples of charge forming devices of this character are disclosed in the copending applications of Wilford H. Teeter, Serial No. 221,372, filed September 22, 1927, which matured to Patent 1,819,526 granted Aug. 18, 20 1931, and Fred E. Aseltine and Wilford H. Teeter, Serial No. 221,371, filed September 22, 1927, which matured to Patent 1,819,495 granted Aug. 18, 1931.

In earlier devices of this type, such as 25 those disclosed in the above mentioned applications, various means have been provided to control the flow of fuel and air under various different operating conditions to secure at all times a mixture having the desired

30 fuel and air ratio. Among the proportioning means employed in these earlier devices is a means for admitting air to the primary mixing chambers in advance of the fuel jet to reduce the velocity of flow past the jet

35 and prevent a tendency to provide an over-rich mixture as the engine speed increases, such an air admitting means being disclosed in the above mentioned application of Wil-

ford H. Teeter, Serial No. 221,372. This air 40 admitting means in the devices heretofore known was controlled wholly by the size of the air passage or passages and the pressures effecting flow therethrough and has not proved entirely satisfactory in its operation,

45 as it has been found desirable to vary the mixture proportions under certain operating conditions, and for this purpose to increase the effective suction on the jets.

The present invention relates primarily to 50 a charge forming device of the type shown in

the above mentioned Teeter application and its principal object is to provide a means to prevent enrichment of the mixture under certain operating conditions, which is automatically controlled in its action to provide an enriched mixture under other operating conditions to supply the increased power which these operating conditions demand. More specifically, it is an object of the invention to provide means for admitting air to the mixture passage posterior to the jet to prevent mixture enrichment, and to provide means for reducing the admission of such air as the engine speed increases, in order to enrich the mixture at high engine speed.

These objects are accomplished according to the present invention by the provision of passages admitting air to the primary mixture passages between the nozzles and the outlet ends of said mixture passages. These air 70 passages terminate adjacent the primary throttle, which is so designed that passages are closed as the mixture passages are opened, the air passages being fully closed on maximum throttle opening.

Further objects and advantages of the present invention will be apparent from the following description, reference being had to the accompanying drawing wherein a preferred embodiment of one form of the pres- 80 ent invention is clearly shown.

In the drawing:

Fig. 1 is a longitudinal vertical section through a charge forming device in which the present invention is embodied.

85 Figs. 2 and 3 are sections on the lines 2—2 and 3—3 of Fig. 1.

Fig. 4 is a detail view of the primary throttle.

90 The drawing discloses a charge forming device comprising a main air manifold 10 having three outlet branches, the middle branch 12 being shown herein. Each of these branches communicates with one of the intake ports 14 of a multicylinder engine and each is provided with an attaching flange 16 for securing the manifold to the engine block in the usual manner. Adjacent the inlet of the manifold 95 is provided a flange 18, to which the main car- 100

buretor unit is adapted to be attached, as shown in Fig. 1.

The carburetor unit comprises a main housing 20, having an attaching flange 22, adapted to be secured to the flange 18, by screws 24. An air inlet horn 28 is secured in position to register with an opening in the upper wall of the housing 20 in any suitable way. A casting 30, having certain dash pot cylinders and fuel passages formed therein, as will be fully described later, is secured in any suitable way to the bottom wall of the housing 20, as shown in Fig. 1, and a sheet metal fuel bowl 32 is held tight against an annular shoulder 34 on the housing 20, by a screw 35, or in any other suitable way. Fuel is conducted from the main source of supply to the fuel bowl through a conduit, not shown herein, and the flow of fuel to the bowl is controlled by a float 36 operating in the usual manner to maintain a substantially constant level of fuel therein.

Fuel flows from the bowl 32 to a plurality of primary fuel nozzles 38, one of which is located in each of the primary mixture passages 40, the construction of which is briefly described hereinafter. The fuel conduit between the fuel bowl and the nozzles comprises a vertical fuel passage 42, communicating at its upper end with a horizontal fuel canal 44, which connects with each of the fuel nozzles through orifices 46. Fuel is admitted from the fuel bowl to the passage 42 at all speeds through a fixed metering orifice 48, and at high speeds additional fuel is admitted through an orifice 50, controlled by a valve 52, in the manner set forth in the above mentioned applications.

Fuel is lifted from the fuel bowl through the above described fuel passages and nozzles to the mixture passages by the suction maintained therein. Closing movements of the throttle cause a reduction in suction in the mixture passages which might permit the fuel column to drop sufficiently to cause a temporary fuel starving of the engine. To prevent such an occurrence, a check valve 54 is provided in an enlarged chamber 56 at the junction of the channels 42 and 44, and on reduction of suction in the mixing chamber, is adapted to seat on an annular bead 57 formed on the bottom of the chamber 56, thus preventing any downward flow of fuel. Each primary fuel nozzle is provided with an open upper end forming a main fuel outlet and a secondary fuel outlet comprising two orifices 60 and 62 in the side of the nozzle near the bottom of the mixture passage. At relatively high speeds the suction in the mixture passage is enough to draw fuel from the main outlet in the top of the nozzle as well as from the orifices 60 and 62. At idling or low speed operation under load, however, the suction is sufficient to lift fuel only to some point between the top of the nozzle and orifices 60

and 62, fuel flowing through these orifices by action of gravity. Each nozzle is provided with a restricted fuel metering orifice 63. The primary mixture passages 40 are parallel to each other and close together, as indicated in Figs. 2 and 3, and when the carburetor is attached to the manifold, these passages register with conduits which convey the primary mixture to the secondary mixing chamber, as fully described in the prior applications above referred to.

A single throttle valve 64 which extends across the primary mixture passages controls the flow therethrough and is provided with grooves 66 which register with said mixture passages. This throttle is operated by means fully disclosed in the above mentioned applications and which forms no part of the present invention. The throttle is held against longitudinal movement by means of a screw 67 engaging a groove 69 in the periphery of the throttle. The middle primary mixture passage registers with a tube 68, secured in the manifold outlet branch 12, and which conveys the primary mixture to the secondary mixing chamber in that specific branch of the manifold.

As has been indicated above, the present invention relates to means for automatically regulating the mixture proportions so that the enrichment of the mixture at low and intermediate speeds is prevented while enrichment of the mixture at high speeds to give the necessary power for satisfactory high speed operation can be secured. To effect this result, a plurality of passages 70 have been provided. These passages are diagonal with respect to the primary mixture passages and connect the primary mixture passages with the main air chamber, hereinafter referred to. There are three of these passages, one for each mixture passage 40, and said passages terminate adjacent the primary throttle valve 64, as indicated in Fig. 1. The arrangement is such that when the throttle valve 64 occupies its closed position, as indicated in Fig. 1, the passages 70 are wide open. These passages remain wide open during operation at low speed and are effective to admit sufficient air to the primary mixture passages at speeds up to that at which the secondary throttle, hereinafter described, begins to open to reduce the velocity of flow of air at the nozzles 38 sufficiently to prevent the formation of a velocity head as such nozzles, and by preventing the formation of a velocity head at the nozzles, the quantity of fuel drawn from said nozzles may be controlled in accordance with the opening of the main air valve so as to form a fuel mixture of substantially constant proportions, as long as the passages 70 remain open. As will be set forth more fully hereinafter, at speeds above that at which the main air throttle is opened, there is a tend-

ency for the mixture to become leaner and at such speeds the valve 52 is opened to offset this tendency. Also at speeds above that at which the main air throttle begins to open, the primary throttle 64 in moving toward its fully open position gradually closes the passages 70 until when the throttle is in its fully open position said passages are completely closed. The closing of these passages by the primary throttle greatly reduces the amount of air admitted to the primary mixture passages in advance of the nozzle, finally entirely preventing the admission of such air. This reduction and final elimination of the flow of air into the primary mixture passages in advance of the nozzle is effective to create a velocity head at the nozzles 38, thus enriching the mixture at high speeds, which is necessary to supply the requisite power for satisfactory operation at such speeds.

Nearly all the air entering the carburetor flows through the air horn 28, controlled by a main air valve 71, normally held against the seat 72, by a spring 74, received between the valve and a flange 76, projecting from a sleeve 78, slidably mounted on a stationary guide sleeve 80, fixed in the housing 20, and serving as a guide for the stem 82, to which the air valve is secured. When it is desired to choke the carburetor, the flange 76 is adapted to be lifted by an arm 83 until the upper end of the sleeve 78 engages the valve to hold it against its seat, as fully described in the above applications. Sufficient air to carry the starting fuel from the nozzles to the intake ports is admitted through an elongated slot 84, formed in a plate 86, secured to the housing 20, as shown in Fig. 1.

The valve 71 admits air to a main air chamber 88 from which air flows to the primary mixture passages through an opening 90 in the floor of the air chamber and to the secondary mixing chambers through a passage 92, which connects with the inlet of the manifold 10. A manually operable throttle 94 and a suction operated valve 96 control the flow of air through the passage 92 and the operating connection and mode of operation of such valves are fully disclosed in the cPending application of Fred E. Aseltine et al., Serial No. 288,683, filed June 8, 1928.

While the specific means for operating the two throttle valves constitutes no part of the present invention, the mode of operation of these valves will be briefly set forth in order to enable the present invention to be clearly understood. The valves are operated by a common operating mechanism which is so constructed that it permits the primary throttle to make a certain predetermined movement independently of the throttle 94, and a part of the movement of the primary throttle is effected simultaneously with the movement of the throttle 94. For instance, during engine operation at all speeds lower

than that corresponding to a vehicular speed of substantially 20 miles per hour on a level, the primary throttle is opened and the throttle operating mechanism is so designed that the throttle 94 begins to open at the speed referred to.

It has been found that unless some compensating means is provided, the velocity through the mixture passages is great enough under substantially all operating conditions to build up a velocity head at the fuel nozzles which will effect too great a fuel flow and form too rich a mixture. To prevent this action means has previously been provided to admit air to the primary mixture passages posterior to the nozzles, such a structure being disclosed in copending application No. 221,372. This means, however, has proved only partially effective at speeds below the predetermined speed above referred to and the fuel nozzles have, therefore, been calibrated somewhat smaller than would be theoretically correct to compensate for the relatively slight velocity head created at speeds below 20 miles per hour. At greater speeds than this, it has been found necessary to provide other compensating means and to this end the air throttle 94 is provided. It has been found in practice, however, that the opening of this throttle effected too rapid a reduction in the velocity at the nozzles resulting in the entire elimination of the velocity head at a speed of about 30 miles per hour. Since the presence of some velocity head is necessary to effect a proper fuel flow, the mixture becomes too lean when the air throttle is opened and the valve 52 has been provided to supply additional fuel to make up for this deficiency and prevent leaning of the mixture at intermediate speeds.

It is desirable, however, to provide an enriched mixture during operation at relatively high speeds to provide the additional power necessary for satisfactory operation. As stated previously, this is accomplished according to this invention by utilizing the throttle 64 to close the air passages 70 as the throttle is opened, thus making use of an increased velocity head at the nozzles to enrich the mixture at high speeds. In fact, by properly designing the throttle and properly positioning the passages 70 with respect thereto, the air flow through passages 70 may be so restricted after the throttle 94 begins to open as to increase the flow from the jets sufficiently to eliminate the necessity of the valve 52. In the preferred embodiment of the invention disclosed herein, however, the primary throttle is designed to restrict the passages 70 so as to enrich the mixture at high speeds only and the valve 52 is utilized to properly proportion the mixture for intermediate speed operation.

On opening of either or both the throttle

valves 64 or 94, the suction in the air chamber 88 is increased and the valve 71 is opened against the pressure of its spring to admit additional air and increase the quantity of mixture supplied to the engine. The opening of the valve must be retarded to some extent, however, to prevent fluttering of said valve and to prevent the admission of sufficient air to temporarily lean the mixture. A dash pot is provided to accomplish these results comprising a cylinder 100, formed in the casting 30, and a piston 102, slideable within the cylinder and secured to the lower end of the valve stem 82 in any desirable manner, as by means of a nut 104, as shown in Fig. 1. The construction of this dash pot is immaterial in so far as the present invention is concerned, and any known form of dash pot may be employed to control the movement of the air valve 71.

While no means for pumping additional fuel into the mixture passages or into the secondary air passage 92 is disclosed herein, it will be understood that any form of fuel pump, such for instance, as one of those disclosed in the above mentioned applications, may be provided if desired. It will also be understood, however, that the presence of such a fuel pump is immaterial so far as the present invention is concerned, and that the latter may be employed in a device having no means for pumping additional fuel into the mixture passage to enrich the fuel for acceleration.

A plurality of secondary mixing chambers are provided, one of which is associated with each outlet branch of the manifold and which are of identical construction. Each of these mixing chambers comprises a Venturi tube 110, provided with an external rib 112, which is clamped between the manifold and the engine block when the manifold is secured to said block, as indicated in Fig. 1. When so assembled, the outlet of the primary mixture conduit associated with said Venturi tube terminates at the point of greatest suction therein so that the Venturi tubes serve to maintain a high velocity of flow past the end of the primary mixture conduits under all operating conditions in order to maintain a relatively high suction within said conduits. These Venturi tubes constitute no part of the present invention, but function in the manner fully set forth in the above mentioned applications.

While the form of embodiment of the present invention as herein disclosed, constitutes a preferred form, it is to be understood that other forms might be adopted, all coming within the scope of the claims which follow.

What is claimed is as follows.

1. A charge forming device for internal combustion engines having in combination a plurality of mixture passages, means admitting fuel and air to each of said mixture

passages, means admitting additional air to each mixture passage, and means for simultaneously varying the flow through all of said mixture passages and said means for admitting additional air so that the supply of additional air is reduced as the flow through said mixture passages is increased. 70

2. A charge forming device for internal combustion engines comprising a plurality of mixture passages, a plurality of supplemental air inlet passages, each of which is adapted to admit air to one of said mixture passages, and a single throttle valve for controlling the flow through all of said mixture passages and all of said supplemental air 80 passages. 75

3. A charge forming device for internal combustion engines comprising a plurality of mixture passages, a plurality of supplemental air inlet passages, each of which is adapted to admit air to one of said mixture passages, and a single throttle valve for simultaneously increasing the area of the outlets of all of said mixture passages and decreasing the area of all of said supplemental air 90 inlet passages. 85

4. A charge forming device for internal combustion engines comprising a plurality of primary mixture passages, means for supplying fuel and air to each of said mixture passages, a secondary mixing chamber into which said mixture passages deliver, a secondary air passage adapted to supply air to said secondary mixing chamber, a plurality of supplemental air passages, each of which is adapted to supply air to one of said mixture passages and means for simultaneously varying the flow through the secondary air passage, all of said supplemental air passages and the primary mixture passages. 100 95

5. A charge forming device for internal combustion engines comprising a plurality of primary mixture passages, means for supplying fuel and air to each of said mixture passages, a secondary mixing chamber into which said mixture passages deliver, a secondary air passage adapted to supply air to said secondary mixing chamber, a plurality of supplemental air passages, each of which connects one of said primary mixture passages with the secondary air passage and means for simultaneously varying the flow through the mixture passages and all of said air passages. 110 115

6. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a secondary air passage supplying air to the secondary carburetor, a primary throttle in the primary mixture passage controlling the flow of mixture 120 125 130

therethrough and the supplemental air inlet and means operated thereby for controlling the flow through the secondary air passage.

7. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a secondary air passage supplying air to the secondary carburetor, a primary throttle in the primary mixture passage controlling the flow of mixture therethrough and the supplemental air inlet, a valve in the secondary air passage and means connecting said valve to the primary throttle for simultaneous operation therewith.

8. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a secondary air passage supplying air to the secondary carburetor, a primary throttle in the primary mixture passage controlling the flow of mixture therethrough and the supplemental air inlet, means in the secondary air passage for controlling the flow therethrough, and means for operating said flow controlling means by the primary throttle to permit an increased flow through the secondary air passage as the flow through the supplemental air inlet is reduced.

9. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a secondary air passage supplying air to the secondary carburetor, a primary throttle in the primary mixture passage adapted to control the flow of mixture therethrough and the flow of supplemental air thereto, said throttle being constructed to decrease the quantity of supplemental air admitted as the flow of mixture is increased.

10. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a secondary air passage supplying air to the secondary carburetor, a primary throttle in the primary mixture passage adapted to close the supplemental air inlet as the throttle is opened, and

a valve in the secondary air passage connected to the throttle for operation thereby, said valve being opened as the throttle is opened.

11. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a primary throttle in the primary mixture passage adjacent the supplemental air inlet and adapted to control the admission of air therethrough, and the volume of mixture delivered to the secondary carburetor.

12. A charge forming device for internal combustion engines comprising a primary mixture passage, a secondary carburetor into which the primary mixture passage delivers a primary mixture of fuel and air, fuel and air inlets for said primary mixture passage, a supplemental air inlet supplying air to said primary mixture passage, a primary throttle in the primary mixture passage adjacent the supplemental air inlet and adapted to close the supplemental air inlet as the primary mixture passage is opened.

13. A charge forming device for internal combustion engines comprising a primary mixture passage, a secondary mixing chamber into which the primary mixture passage delivers a primary mixture of fuel and air, fuel and air inlets for the primary mixture passage, a secondary air passage supplying air to the secondary mixing chamber, and a supplemental air passage connecting the primary mixture passage with the secondary air passage.

14. A charge forming device for internal combustion engines comprising a primary mixture passage, a secondary mixing chamber into which the primary mixture passage delivers a primary mixture of fuel and air, fuel and air inlets for the primary mixture passage, a secondary air passage supplying air to the secondary mixing chamber, a valve in the secondary air passage adapted to be closed under certain operating conditions, and a supplemental air passage connecting the primary mixture passage with the secondary air passage at a point anterior to said valve, whereby air is admitted to the primary mixture passage independently of the position of said valve.

15. A charge forming device for internal combustion engines comprising a primary mixture passage, a secondary mixing chamber into which the primary mixture passage delivers a primary mixture of fuel and air, fuel and air inlets for the primary mixture passage, a secondary air passage supplying air to the secondary mixing chamber, a supplemental air passage connecting the primary mixture passage with the supplemental

air passage, and a throttle valve in the primary mixture passage at a position where it controls the supplemental air passage.

16. A charge forming device for internal combustion engines comprising a primary mixture passage, a secondary mixing chamber into which the primary mixture passage delivers a primary mixture of fuel and air, fuel and air inlets for the primary mixture passage, a secondary air passage supplying air to the secondary mixing chamber, an air supply chamber adapted to admit air to the primary mixture passage and the secondary air passage, and a supplemental air passage connecting the secondary air passage with the primary mixture passage.

17. A charge forming device for internal combustion engines comprising a primary mixture passage, a secondary mixing chamber into which the primary mixture passage delivers a primary mixture of fuel and air, fuel and air inlets for the primary mixture passage, a secondary air passage supplying air to the secondary mixing chamber, an air supply chamber adapted to supply air to the secondary air passage and the primary mixture passage at all times, a throttle in the primary mixture passage and a supplemental air passage adapted to convey air from the secondary air passage to the primary mixture passage only when the throttle is in certain positions.

18. A charge forming device for internal combustion engines comprising a mixture passage, a fuel inlet therefor, an air inlet therefor anterior to said fuel inlet, a by-pass supplying air to said mixture passage posterior to and relatively close to the fuel inlet, said by-pass being of sufficient capacity to materially reduce the velocity of flow past the fuel inlet, and a restriction in the mixture passage between the fuel inlet and the by-pass.

19. A charge forming device for an internal combustion engine having in combination a mixture passage, a fuel nozzle therein, a main air inlet admitting air to said mixture passage anterior to said fuel nozzle, a throttle for said mixture passage, a second air inlet simultaneously admitting air to said mixture passage posterior to the fuel nozzle and anterior to the throttle, said throttle being so constructed as to vary the area of the second air inlet as the throttle is moved to vary the engine speed.

20. A charge forming device for an internal combustion engine having in combination a mixture passage, a fuel nozzle therein, a main air inlet admitting air to said mixture passage anterior to said fuel nozzle, a throttle for said mixture passage, a second air inlet simultaneously admitting air to said mixture passage posterior to the fuel nozzle and anterior to the throttle, said throttle being so constructed as to reduce the area of

said second air inlet as the throttle is opened.

21. A charge forming device for internal combustion engines comprising a primary carburetor, fuel and air inlets therefor, a supplemental air inlet for said primary carburetor, a secondary carburetor into which said primary carburetor delivers a primary mixture of fuel and air, and means including a primary throttle for simultaneously varying the flow of mixture through the primary carburetor and the flow of air through said supplemental and secondary air passages.

22. A charge forming device for internal combustion engines comprising a primary carburetor, fuel and air inlets therefor, a supplemental air inlet for said primary carburetor, a secondary carburetor into which said primary carburetor delivers a primary mixture of fuel and air, and means for increasing the flow of mixture through the primary carburetor and the flow of air through the secondary air passage, while simultaneously decreasing the flow of air through the supplemental air passage.

In testimony whereof I hereto affix my signature.
